UNITED STATES PATENT OFFICE

2,438,752

INHALER

Milford Lee Kahn, Chicago, Ill., assignor of one-half to Roger N. Kinkella, Chicago, Ill.

Application July 11, 1946, Serial No. 682,742

3 Claims. (Cl. 128—200)

1

This invention relates to new and useful improvements and structural refinements in inhalers, and the principal object of the invention is to provide a device of the character herein described, which may be conveniently and effectively employed for applying medication to the nasal passages in the form of spray or vapor, without the use of conventional devices, such as usually consist of atomizers operated by compressing rubber bulbs.

A further object of the invention is to provide an inhaler which, by virtue of its simplified construction, is readily adapted for carrying on the person of the user, thereby being available at any time and as often as required.

Another object of the invention is to provide an inhaler which may be readily disassembled for purposes of cleaning, inspection, repair, or refilling with the medication employed therein.

An additional object of the invention is to provide an inhaler which is light in weight, pleasing in appearance, and which will not easily become damaged.

A still further object of the invention is to provide an inhaler which will readily lend itself to economical manufacture.

With the above more important objects in view and such other objects as may become apparent as this specification proceeds, the invention consists essentially of the construction and arrangement of parts as shown in the accompanying drawings in which:

Figure 1 is cross-sectional view of the invention, showing the same in the closed position.

Figure 2 is a further cross-sectional view, but showing the invention in readiness for use,

Figure 3 is a top plan view of the invention.

Figure 4 is a side elevation of the removable cover used in the invention and showing the same partially broken away to reveal its construction.

Figure 5 is a cross-sectional view, taken substantially in the plane of the line 5—5 in Figure 1, and

Figure 6 is a cross-sectional view, taken substantially in the plane of the line 6—6 in Figure 1.

Like characters of reference are used to designate like parts in the specification and throughout the several views.

Referring now to the accompanying drawings in detail, the invention consists of an inhaler designated generally by the reference character 10, the same embodying in its construction a vertically disposed, substantially cylindrical casing 11, having a closed bottom 12 and being

2

opened at its upper end, which is internally threaded as at 13.

The threaded portion 13 is adapted to receive an externally threaded portion 14 provided on a cover 15, the latter being best illustrated in Figure 4 and being designed for removable positioning at the open end of the casing 11, as will be clearly apparent from the accompanying drawings. It will be noted that the cover 15, in effect, constitutes a continuation of the casing 11.

The casing 11 is also provided adjacent the closed end thereof with an internally threaded portion 16, this being engageable with an externally threaded portion 17 formed on the lateral surface of a cylindrical receptacle 18. The receptacle 18 is also formed with a closed bottom 19 and the upper end thereof is open and internally threaded as at 20 to removably receive a dome-like cap 21.

The cap 21 is provided with an inhaling opening 22, while the inner surface of the cover 15 is formed with a convex seat 23. It will be noted that when the cover 15 is positioned on the casing 11, the seat 23 will engage and close the opening 22 in the cap 21.

Atomizing means designated generally by the reference character 24 are provided in the receptacle 18, the same consisting of an air tube 25 and a liquid tube 26 which are secured in position by means of suitable ribs 27 extending diametrically of the receptacle 18.

It will be noted that the air tube 25 extends upwardly from the bottom end 19 of the receptacle and terminates at its upper end adjacent the cap 21. The liquid tube 26 extends from somewhat above the bottom end 19 and is laterally arcuated as at 28 toward the upper end of the tube 25.

The lower end of the aforementioned tube 25 terminates, in effect, in the bottom 19 of the receptacle and forms an opening 29. This opening or aperture is offset with respect to a further opening or passage 30 provided in the bottom 12 of the casing 11. A gasket-like washer 31 is interposed between the bottoms 12 and 19, as will be clearly apparent from the accompanying drawings.

When the invention is placed in use, the medication 32 in liquid form is poured into the receptacle 18 by first removing the cover 15 and then the cap 21. Thereupon the cover and cap are replaced and the device may be conveniently carried in the user's pocket, since the seat 23 of the cover 15 engages and closes the opening 22.

of the cap 21, as has been already explained and as is best illustrated in the accompanying Figure 1.

When the inhaler is in this position, the receptacle 18, more specifically, the bottom 19 of the receptacle, contacts the washer 31 and it will be observed that in this manner, the openings 29 and 30 are closed.

When it is desired to use the inhaler, the cover 15 is removed and the receptacle 18, as a whole, is rotated, so that the engaging thread portions 16 and 17 separate the bottom 19 from the washer 31, as is best shown in Figure 2.

In this position, an air passage exists through the openings 30 and 29 and into the tube 25 and by applying the inhaler to the nose, so as to engage the opening 22 with the nostril, air may be drawn through the passages 30 and 29 and through the tube 25 as indicated by the arrows 33.

During this action, the liquid 32 will be drawn upwardly through the tube 26 and will be atomized at the junction of the tubes 25 and 26 in the well known manner.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. An inhaler comprising in combination, a vertically disposed, substantially cylindrical casing having a closed bottom and being open at its upper end, a cover removably positioned at the open end of said casing and constituting a continuation thereof, an internally threaded portion in said casing, a cylindrical receptacle and an externally threaded portion thereon, said receptacle being positioned in said casing and said threaded

portions being in engagement, said receptacle also having a closed bottom and being open at its upper end, a dome-like cap removably positioned at the open end of said receptacle and being formed with an inhaling opening, a seat in said cover normally closing said opening, atomizing means positioned in said receptacle and comprising an air tube and a liquid tube, said air tube extending upwardly from the bottom of said receptacle and terminating adjacent said cap, said liquid tube extending upwardly from above the bottom of said receptacle and being arcuated to terminate adjacent the upper end of said air tube, the lower end of said air tube forming an aperture in the bottom of said receptacle, the bottom of said casing having a further aperture formed therein, the bottoms of said receptacle and of said casing normally being in contact and closing said apertures.

2. In an inhaler, a substantially cylindrical casing including a screw-threaded portion and provided with an aperture at the center of one of its ends, a receptacle provided with a further screw-threaded portion and positioned in said casing, said screw-threaded portions being in operative engagement, an end of said receptacle being formed with an eccentrically disposed aperture and said eccentrically disposed aperture normally being closed by the apertured end of said casing.

3. The device as defined in claim 2 wherein the aperture in said casing is normally closed by the apertured end of said receptacle.

MILFORD LEE KAHN.
